[57] CLAIM

The ornamental design for an abutment for a dental implant, as shown and described.

DESCRIPTION

FIG. 1 is a side elevational view of an abutment for a dental implant showing our new design, the other side being identical;

FIG. 2 is a top plan view thereof, the bottom being identical;

FIG. 3 is a left end elevational view thereof;

FIG. 4 is a right end elevational view thereof;

FIG. 5 is a side elevational view of a second embodiment thereof, the other side being identical;

FIG. 6 is a top plan view thereof;

FIG. 7 is a side elevational view of a third embodiment thereof, the other side being identical;

FIG. 8 is a top plan view thereof, the bottom being identical;

FIG. 9 is a left end elevational view thereof;

FIG. 10 is a right end elevational view thereof;

FIG. 11 is a side elevational view of a fourth embodiment thereof, the other side being identical;

FIG. 12 is a top plan view thereof;

FIG. 13 is a perspective view of the embodiment shown in FIG. 1;

FIG. 14 is a perspective view of the second embodiment shown in FIG. 5;

FIG. 15 is a perspective view of the third embodiment shown in FIG. 7; and,

FIG. 16 is a perspective view of the fourth embodiment shown in FIG. 11.
